UNITED STATES PATENT OFFICE

WILLIAM C. TYLER, OF JOLIET, ILLINOIS, ASSIGNOR TO WILLIAM E. PRATT MFG. CO.,
OF JOLIET, ILLINOIS, A CORPORATION OF ILLINOIS

SCREW JACK

Application filed October 1, 1931. Serial No. 566,326.

This invention relates to screw jacks and more particularly to screw jacks of the double-lift type.

One of the objects of the invention is to provide a screw jack of simple and staunch construction which is designed to be collapsed into a compact unit occupying a minimum of space and which may be extended to the desired height for lifting automobiles and the like. Another object is to provide a new jack construction in which many of the working parts are housed in such a manner as to exclude dirt, grit, etc. Other objects and advantages will appear as the specification proceeds.

The invention is illustrated in its preferred embodiments in the accompanying drawings, in which—

Figure 1 is a side view in elevation of one form of jack embodying my invention; Fig. 2, a top plan view; Fig. 3 a vertical sectional view, the section being taken as indicated at line 3 of Fig. 2; Fig. 4, a broken plan sectional view, the section being taken as indicated at line 4 of Fig. 3; Fig. 5, a sectional view similar to the sectional view shown in Fig. 3, but showing the lifting members in partially extended position; Fig. 6, a broken sectional view of a modified form of jack embodying my invention; Fig. 7, a transverse sectional view, the section being taken as indicated at line 7 of Fig. 6; Fig. 8, a sectional view of parts within the casing, the section being taken as indicated at line 8 of Fig. 6; Fig. 9, a plan view of the locking washer employed; and Fig. 10, a sectional view of the casing employed with the modified form of screw jack.

In the illustration given in Figs. 1 to 5, A designates a jack casing which is provided with a base A' and a bore A². The casing is also provided with the usual extension A³ in which the actuating shaft 1 is rotatably supported. The shaft is provided with a bevel gear member 2.

As illustrated more clearly in Fig. 3, a tubular extension 3 is provided at the top of the casing A and carries a drive nut 4. The drive nut 4 is confined between member 3 and the casing extension A³. Drive nut 4 is cen-

trally apertured and is provided with a key 5. A sleeve lifting member 6 extends through the drive nut 5 and is provided with a groove 7 which engages the key 5 of nut 4. The sleeve member 6 is provided with an upper internally threaded nut 8 and with a lower internally threaded nut 9. An inner lifting screw 10 engages the upper nut 8. A rotatable screw post 11 engages the lower nut 9 of the sleeve member 6. The screw post 11 is preferably provided with a reduced square end 12 which extends through a square opening in a circular plate 13. The plate or disk 13 is preferably provided at its periphery with a circular groove 14, which is provided with friction indentations or projections 14'.

The base A' of the casing, as illustrated in Fig. 3, is provided with a plunger compartment 15 in which a spring urged plunger 16 is reciprocally guided. The plunger 16 is provided with a rounded end which engages the circular groove 14 of disk 13; this prevents the jack from extending when held upside down.

The screw post 11 is provided at its upper end with a stop pin 17 which is adapted to engage the nut 9 and to lock post 11 to sleeve 6.

In the operation of the jack, with the parts in collapsed position, as shown in Fig. 3, the rotation of drive nut 4 in one direction causes the sleeve 6 to rotate therewith. The screw post 11 being frictionally held against rotation by plunger 16 which engages disk 13, causes sleeve 6 to rise, the rotating nut 9 engaging the threads of the temporarily fixed post 11. As the sleeve 6 rises, it carries the inner screw 10 bodily with it. When the sleeve 6 has reached the upper limit of its travel, the pin 17 engages nut 9 and locks the post 11 to sleeve 6. Continued rotation of nut 5 causes sleeve 6 and the screw post 11 to rotate together, sufficient force being applied to overcome the friction exerted by plunger 16. If in the course of the upward movement of screw 10 the load should be engaged, screw 10 will be held against rotation and will be compelled to rise, the rotating nut 8 serving as a driving nut. The parts are shown in partially extended posi-

90
95
100

tion in Fig. 5. To return the lifting member to the collapsed position shown in Fig. 3, the driving nut is rotated in the opposite direction. Sleeve 6 is lowered as the post 11 again is restrained against rotation by frictional contact with plunger 16.

In the modified form of jack illustrated in Figs. 6 to 10, B represents a hollow jack casing provided with a base B' and an upper 10 casing extension B². The upper casing extension B² rotatively supports a drive rod 1 which is equipped with a bevel gear 2. A collar 3 is carried by casing B and supports in turn drive nut 4. Drive nut 4 is centrally apertured and is provided interiorly with a key 5.

The casing B is provided with a vertical groove 18 which opens into an enlarged chamber 19 at the top of the casing and into 20 a similar large chamber 20 at the bottom of the casing. The groove 18 is provided with oppositely disposed curved cam walls 21 and 22 at its upper and lower ends respectively.

25 A sleeve member 23 extends through drive nut 4 and into the bore of the jack casing. On its outer side it is provided with a groove or keyway 24 which is engaged by key 5 of drive nut 4. Interiorly, the sleeve member 23 is equipped with upper and lower drive nuts and is the same in construction as sleeve member 6 heretofore described. An inner lifting screw 25, similar to lifting screw 10, heretofore described, engages the 30 upper nut of sleeve 23. A rotatably mounted screw post 26 extends through the lower nut of sleeve 23. The screw post 26 is provided with a vertical groove 27 which extends substantially through the length of the post.

40 As shown more clearly in Fig. 6, sleeve 23 is provided at its lower end with a reduced portion 28 which has its lower edge flared outwardly to provide a retaining flange. An annular ring 29 is secured upon the end 28 by the retaining flange and is connected by 45 depending lugs 30 to a locking washer 31. As shown more clearly in Fig. 9, washer 31 is provided with openings 32 through which lugs 30 extend. An inwardly turned key 33 50 engages the groove 27 of the screw post 26. A pair of diametrically disposed lugs 34 engage grooves 18 in the casing B.

Disposed in the lower compartment or chamber 20 of the casing and encircling screw post 26 is a short coil spring 35. The purpose of the spring is to urge the washer 31 into contact with the cam wall 22 when the sleeve 23 is to be started on its upward travel.

60 In the operation of the modified form of jack illustrated in Figs. 6 to 10, assuming that the parts are in collapsed position, the rotation of drive nut 4 and sleeve 23 in one direction causes the sleeve to rise, the inner 65 screw being held against rotation in the fol-

lowing manner. The rotation of the washer 31 in one direction brings it into contact with the straight wall of groove 18 and prevents further rotation of the washer. Since the washer 31 is provided with an inner key 33 70 engaging groove 27 of post 26, post 26 is also held against rotation. Engagement of the lower nut of sleeve 23 with the temporary fixed post 26 causes the sleeve to rise, bearing with it the inner screw 25. At the same time, the sleeve 23 carries washer 31 by means of the connecting lugs 30 and ring 29. When the sleeve 23 reaches the upper limit of its travel, the washer 31 enters the enlarged chamber 19 and the lugs 34 slide over cam 21 as the 75 sleeve rotates. The sleeve 23 and screw post 26 are now free to rotate together. Assuming that the inner screw 25 has been brought into engagement with the load, continued rotation of the sleeve 23 will cause the upper nut to drive screw 25 in an upward direction. In returning the screw parts to their collapsed position, the nut is turned in the opposite direction. The projections 34 engage the 80 straight wall of the groove 18 and prevent further rotation of the washer 31. With the screw post again temporarily locked against rotation, the sleeve 23 descends to its original position, the washer 31 entering the lower 85 enlarged chamber 20 and rotating freely 90 therein.

In both forms of jacks illustrated, it will be observed that the inner screw post is rotatably mounted and is restrained against rotation during the upward movement of the 100 sleeve members. In one case, frictional means is employed to retard rotation while in the other case positive means are provided to prevent rotation of the screw except when the sleeve has reached the limits of its travel, at which points the screw is free to rotate in 105 one direction.

The foregoing detailed description has been given for clearness of understanding only and no unnecessary limitations should be understood therefrom, but the appended 110 claims should be construed as broadly as permissible in view of the prior art.

I claim:

1. A jack comprising, a hollow casing, a 115 drive nut rotatably mounted therein, a sleeve slidably keyed to said nut, said sleeve being provided interiorly with upper and lower nuts, a hollow lifting screw engaging said upper nut, a rotatably mounted screw post 120 engaging said lower nut, and means for restraining rotation of said screw post.

2. A jack comprising, a hollow casing, a drive nut rotatably mounted in said casing, a sleeve member slidably keyed to said nut, 125 said sleeve being provided interiorly with upper and lower threaded portions, a lifting screw engaging said upper threaded portion, a rotatably mounted screw post engaging said lower threaded portion, and means for 130

- restraining rotation of said screw post during vertical movement of said sleeve.
3. A jack comprising, a hollow casing, an annular drive nut mounted therein, a sleeve 5 slidably mounted in said casing and connected to said nut, said sleeve being provided interiorly with upper and lower nuts, a hollow lifting screw engaging said upper nut, a screw post rotatably mounted in said casing and engaging said lower nut, means for retaining rotation of said screw post until said sleeve reaches the limits of its travel, and means for actuating said drive nut.
4. In a screw jack provided with a hollow casing and a drive nut mounted therein, a rotatable screw post supported in said casing, a pair of threadedly connected and telescoping lifting members, one of said members being threadedly connected with said screw post, and means for restraining the rotation of said screw post.
5. A screw jack comprising, a hollow casing, a disk rotatably mounted in said casing, a screw post fixed to said disk, means for exerting friction against said disk, an annular nut carried by said casing, a sleeve member extending through said nut and slidably keyed thereto, said sleeve member being threadedly connected to said screw post, and a hollow lifting screw encircling said screw post, and threadedly engaging said sleeve member.
6. A screw jack comprising, a hollow casing, a screw post rotatably mounted therein, means for exerting friction upon said screw post, nested lifting members encircling said screw post, one of said members being threadedly connected therewith, and means for rotating one of said nested lifting members.
7. A screw jack comprising, a hollow casing, a disk rotatably mounted in the bottom of said casing, a spring-urged plunger engaging the periphery of said disk, a screw post fixed to said disk and extending upwardly through said casing, a sleeve member provided with a nut engaging said screw post, a hollow lifting screw threadedly engaging said sleeve, a nut rotatably mounted in said casing and keyed to said sleeve, and means for actuating said nut.
8. A screw jack comprising, a hollow casing, an inner screw rotatably mounted therein, means for yieldably retarding the rotation of said inner screw, a sleeve member equipped with a nut engaging said inner screw, a lifting screw threadedly engaging said sleeve member, stop means carried by said inner screw and adapted to engage said sleeve nut, and means for rotating said sleeve.
9. A screw jack comprising, a hollow casing, a screw post rotatably mounted therein, a lifting member threadedly engaging said post, and cooperating means in said casing
- and associated with said post for preventing rotation of said post except when said lifting member reaches the limit of its vertical travel.
10. A screw jack comprising, a hollow casing, a screw post rotatably mounted therein, a sleeve member threadedly engaging said post, a lifting screw in threaded relation with said sleeve, and positive means for preventing rotation of said screw post until said sleeve reaches the limit of its vertical travel.
11. A jack comprising, a hollow casing having a vertical groove in the walls of the bore, the ends of the bore being larger in diameter than the main bore, a screw post rotatably mounted in said casing, and having a vertical groove, a sleeve member equipped interiorly with upper and lower nuts, said lower nut being in engagement with said screw post, a lifting screw engaging said upper nut, and locking means carried by said sleeve member and equipped with a lug engaging the groove of said screw post and with a lug engaging the vertical groove in the wall of the casing to prevent rotation of said screw post except when said second-mentioned lug reaches the enlargements at the ends of the bore.
12. A jack comprising, a hollow casing having a vertical bore and a vertical groove therein, one end of the bore being of larger diameter than the main bore and provided with cam shoulders joining the enlargement with the walls of the groove, a screw post rotatably mounted in said casing and provided with a vertical groove, a sleeve threadedly engaging said screw post, and a locking member carried by said sleeve and provided with projections engaging the groove of said screw post and the groove of said casing.
13. A screw jack comprising, a hollow casing having a vertical groove in the walls of the bore and an enlargement in the base of the casing communicating with said groove, a screw post rotatably mounted in said casing, a lifting member threadedly engaging said post, said post being provided with a vertical groove, a locking member carried by said lifting member and equipped with lugs engaging the groove of said post and the groove of said casing, and a spring mounted in the base of said bore and adapted to urge said locking member in an upward direction.
14. A jack comprising, a hollow casing provided with a vertical groove and an enlargement in the base of the casing communicating with said groove, said groove being provided with a cam shoulder connecting said enlargement with a wall of said groove, a screw post rotatably mounted in said casing and provided with a vertical groove, a lifting member in threaded engagement with said screw post, a lifting screw in threaded relation with said lifting member, a locking member carried by said lifting member and provided with projections engaging the

groove of said post and the groove of said casing, and a spring in the base of said casing and adapted to urge said locking member toward said cam shoulder.

- 5 15. A jack comprising, a hollow casing equipped with a plurality of vertical grooves and enlargements at the ends of the casing communicating with the grooves, a screw post rotatably mounted in the casing and provided
10 with a vertical groove, a sleeve member equipped with upper and lower nuts, said lower nut engaging said screw post, a lifting screw engaging said upper nut, and a locking washer carried by said sleeve member and provided with projections engaging
15 the groove of said post and the grooves of said casing.
